SELECTIVE COUNTING APPARATUS

Gerald T. Moore, Bedford, and Henry P. Kilroy, Littleton, Mass., assignors to Giddings & Lewis Machine Tool Company, Fond du Lac, Wis., a corporation of Wisconsin

Filed Feb. 2, 1960, Ser. No. 6,280
9 Claims. (Cl. 307—88)

The present invention relates to the art of data processing and is more especially concerned with the selective counting or measuring off of different numbers of time-spaced recurring signals.

It is the general aim of the invention to provide new and improved apparatus for counting or measuring off different selected numbers of signals produced by a recurring signal source, such apparatus being characterized by its simplicity in organization and its reliability in operation.

More specifically, it is an object of the invention to do away with the need for gates of the type commonly employed in this art, and the vacuum tubes or transistors which they require, in apparatus of the type above specified.

Another object of the invention is to bring forth selective counting apparatus characterized particularly in that the over-all ratio of a scaling chain is changed according to the setting of one of a plurality of bi-state elements, preferably magnetic cores, and in which input signals are passed from a source to the scaling chain by the bi-state elements themselves as a result of non-destructive interrogation thereof in response to the input signals.

It is a further object to provide an advantageous system for selectively routing signals or pulses from a first terminal to any one of a plurality of output terminals.

Another object is to provide such a selective routing system employing bi-state elements which function not only as a means selectively set or conditioned to designate the particular output terminal which is to receive the signals, but also as a means for selectively transmitting input signals to the designated output terminal.

Other objects and advantages will become apparent as the following description proceeds, taken in conjunction with the accompanying drawings, in which:

FIGURE 1 is a diagrammatic block-and-line illustration of apparatus for initially setting shifting register cores according to a selected one of a plurality of numbers of signals to be measured off;

FIGS. 2A and 2B, when joined along the indicated junction line, form a diagrammatic block-and-line illustration of selective counting apparatus embodying the features of the invention; and

FIG. 3 is a schematic diagram showing the details of interconnections between exemplary ones of the magnetic cores employed in the apparatus of FIG. 2.

While the invention has been shown and will be described in some detail with reference to a particular embodiment thereof, there is no intention that it thus be limited to such detail. On the contrary, it is intended here to cover all modifications, alterations, and equivalents falling within the spirit and scope of the invention as defined by the appended claims.

2

To make clear the environment of the invention and to illustrate one manner of transferring information to the selective counting means so as to establish different total numbers of signals which will be counted or measured off, FIG. 1 shows a plurality of counting or time selection cores 11-19 which are disposed at the ends of four shifting registers 21-24. Such shifting registers have respective input lines 21a-24a and are made up by a plurality of tandemly connected bi-state elements or magnetic cores 25 in a manner familiar to those skilled in the art.

The magnetic cores here diagrammatically illustrated are of the familiar type often used as components in digital computers and data processing apparatus. Such cores are made of a ferromagnetic material which possesses a substantially rectangular hysteresis characteristic. The cores may, therefore, reside in either of two states, designated as the "0" and "1" states, depending upon the sense or direction of the residual magnetism or flux therein. If a magnetic core residing in a given state receives a magnetomotive force which tends to create flux in the same direction as the residual flux, there will be no appreciable change of flux within the core. Little or no voltage will be induced in an output winding, and the state of the core will be left unchanged. Conversely, if a core is residing in a given one of its two possible states and a magnetomotive force is applied to that core which creates flux in a direction opposite to the sense of the residual flux, and which drives the core to saturation, there will be a considerable flux change within the core and the latter will be switched to and left in its opposite state.

Connected to the input lines 21a-24a are the output terminals 31-34 of a coding device 35. The latter functions to convert signals appearing sequentially on different ones of plural input terminals 36 and representing the respective decimal characters 0-9 into a four place binary code representation. Since the organization and operation of such a decimal-to-binary code conversion device is well known in the art, its details have not been illustrated. For purposes of explanation, it will be assumed that the coding device 35 converts signals representing decimal digits 0-9 into a binary representation according to four-place "5211" code. This code may be best understood by reference to the following table:

Decimal Number	Binary Code			
	5	2	1A	1B
0	0	0	0	0
1	0	0	0	1
2	0	1	0	0
3	0	1	0	1
4	0	1	1	1
5	1	0	0	0
6	1	0	1	0
7	1	1	0	0
8	1	1	0	1
9	1	1	1	1
+	0	0	1	0

50
55
60

It will be seen from the foregoing table, that the four digit places of the binary code are assigned the respective decimal values of 5, 2, 1 and 1. The presence of a

binary "1," as opposed to a binary "0," in each place of a four-place code representation, indicates that the decimal value assigned to that column is to be a part of the sum which equals the decimal number represented. For example, it will be seen from the table above that the decimal number "8" is represented by binary "1's" in the "5" column, the "2" column, and the "1B" column, so that the binary code representation 1101 equals the sum of 5, 2, and 1.

Although the organization of the device 35 is not shown in detail, it may be noted that each time an input signal is applied to one of the input terminals 36, then the four output terminals 31-34 will be simultaneously and momentarily placed at relatively high or low potentials corresponding to the "0's" and "1's" of the binary code for the particular decimal digit which corresponds to that input terminal. For example, if the input terminal 36 which corresponds to the decimal number "8" receives an input signal, then the output terminal 33 will be momentarily and simultaneously elevated to a relatively high voltage, while the terminals 31, 32, and 34 will be left at a relatively low or zero potential. The terminals 31-34 respectively correspond to the "5," "2," "1A" and "1B" digit places of the binary code.

Let it be assumed that each of the shifting registers 21-24 includes, say, twenty-seven tandemly connected cores 25. If thirty decimal digits are fed into the code device 35 by thirty successive signals applied to different ones of the input terminals 36, then the output terminals 31-34 will be energized in thirty successive combinations which, according to the "5211" binary code explained above, correspond to those decimal digits. It may be assumed that the cores 25 in the shifting register all normally reside in the "1" state, and that the first core in each shifting register will be set to the "0" state in response to a high voltage received on the associated output terminals of the coding device. Thus, after each code response of the device 35 and a corresponding setting of the first vertical row of cores 25, a shifting action will be induced (by means not shown) to step the state of the cores, and the decimal number represented thereby, to the cores immediately on the right. In the process, the first vertical row of cores 25 will be returned to the "1" state, so that they are ready to receive the next output signals which appear on the terminals 31-34. From this brief explanation, it will be understood that after thirty input signals representing decimal characters have been received and shifted into the registers 21-24, each group of four vertically aligned cores will store and represent by their states one of the decimal digits. The first decimal digit will be stored in the last vertical row of cores on the right, and the last decimal digit will be stored in the first vertical row of cores on the left.

The first three decimal digits shifted into the registers 21-24 will be stored in the first, second and third vertical rows of cores from the right end of the shifting registers. Since these first three rows of cores on the right are here employed to store information which designates the time or the number of signals to be counted, they are labeled in FIG. 1 as the "Time Section" of the shifting registers. If the very first decimal digit supplied to the coding device 35 and shifted into the register is the number "2," then the four vertically aligned cores at the extreme right in FIG. 1 will be set to the states "0100" from bottom to top since the first core on the right in the shifting register 22 corresponds to the "2" column of the binary code. The core 11 and only this core in that vertical row will be set to the "1" state to represent the decimal number "2."

Let it now be assumed in connection with the exemplary embodiment of the invention which is to be described, that any one of nine "counts" may be selectively

65

70

75

75

measured off. Exemplary "counts" are designated in the first columns of the following table:

Count	Time Selection, sec.	Decimal Representation	Binary Codes			
			5	2	1A	1B
1×10^4	$\frac{1}{2}$	00+	0 0 0	0 0 0	0 1 0	0 0 0
2×10^4	1	001	0 0 0	0 0 0	0 0 1	0 0 0
4×10^4	2	002	0 0 0	0 0 1	0 0 0	0 0 0
1×10^5	5	005	0 0 1	0 0 0	0 0 0	0 0 0
2×10^5	10	010	0 0 0	0 0 0	0 0 0	0 0 1
4×10^5	20	020	0 0 0	0 1 0	0 0 0	0 0 0
1×10^6	50	050	0 1 0	0 0 0	0 0 0	0 0 0
2×10^6	100	100	0 0 0	0 0 0	0 0 0	0 0 1
4×10^6	200	200	0 0 0	1 0 0	0 0 0	0 0 0

To set the cores 11-19 in the time section of the shifting registers so as to designate which of the nine possible "counts" is to be measured off, the first three digits in a set of decimal numbers fed to the terminals 36 will have the decimal values indicated in the third column of the foregoing table. And, after those first three digits have been fully shifted through the registers so that they are represented in binary code by the states of the first three vertical rows of cores on the right, those cores will have the binary states which are represented in the last four columns of the foregoing table. For example, if a count of 1×10^5 signals is desired, the first three decimal characters supplied to the coding device 35 will be 005. When the first two zeros of this expression are shifted into the shifting registers, the first two vertical rows of cores on the right will all be left in their "0" states. The third digit "5" when shifted into the registers will, however, result in the core 16 being set to its "1" state, while the cores 17, 18 and 19 will be left in their "0" states. It will be seen from an inspection of the foregoing table that for each of the nine decimal representations of the nine possible "counts," one and only one of the nine time storage cores 11-19 will be set to the "1" state. The remaining ones of these cores 11-19 will be left in the "0" states. Thus, it will be clear that whenever any one of the nine cores 11-19 is set to its "1" state, the count shown below has been selected by the information received on the input terminals 36.

Time Selection Cores	Selected Time Period, sec.	Selected Number of Signals to be Counted
11	200	4×10^6
12	100	2×10^6
13	50	1×10^6
14	20	4×10^5
15	10	2×10^5
16	5	1×10^5
17	2	4×10^4
18	1	2×10^4
19	$\frac{1}{2}$	1×10^4

If the recurring signals occur at a uniform repetition rate or frequency, the counting off of different numbers of such signals will also measure off different time periods between the beginning and the end of the counting cycles. By way of example, if the recurring signals have a frequency of 20,000 signals per second, then the counting of the different numbers of signals indicated in the foregoing tables will occupy the different time periods listed in the second columns of the two tables.

The cores 11-19 described in connection with FIG. 1 also appear in FIG. 2A and their operation in connection with the selective counting apparatus will be made clear below.

The selective counting apparatus of FIGS. 2A and 2B includes, as a first component thereof, a scaling chain 40 which accepts recurring input signals and produces one output signal for each predetermined number of input signals. This ratio of input to output signals is termed the "scaling ratio." As here shown, the scaling chain is made up of a plurality of bi-state elements, specifically, flip-flop circuits labelled "FF," connected in tandem counting relation. The first flip-flop 41 is connected in tandem relation with six decade scaling units 42-47, and the latter such unit works into a final flip-flop 48. A carry output terminal 50 for the latter flip-flop may be considered as the "completion output terminal" for the entire scaling chain 40 since it will receive a pulse or output signal only at the completion or end of each counting cycle.

Before describing the operation of the scaling chain 40 as a whole, it may be pointed out that the flip-flop circuits used therein are well known to those skilled in the art. Briefly stated, each such flip-flop may, in one form, be made up of two cross-connected vacuum tubes or transistors, each being complementally cut off or conductive when the circuit is in its two possible stable states. Each such flip-flop switches from a "0" to a "1" state and from a "1" to a "0" state in response to two successive input pulses supplied thereto. The flip-flop produces a carry output pulse each time that it switches from the "1" to the "0" state, thus creating one-half as many output pulses as received input pulses. Thus, a single flip-flop operates as a scaling device having a scaling ratio of two.

By connecting two, three or four flip-flops in tandem relation so that the output pulses of one form the input pulses of the next, a unit is created which scales by a factor of 4, 8, or 16, respectively. In the present instance, however, it is desired to utilize units which scale by factors of 10, i.e., each of which produces one carry output pulse for each ten input pulses. Such decade scaling units may take a variety of forms such as the familiar multi-anode counting tubes, but in the present instance are made up of four flip-flop devices interconnected in a special way so that they scale with a ratio of ten rather than a ratio of sixteen. Since the decade units 42-47 are all substantially alike, a description of one will suffice for all.

Referring to the decade unit 42, the four tandemly connected flip-flops therein are designated by the characters A, B, C and D. Ordinarily, four tandemly connected flip-flops would create a scaler or divider unit having a scaling ratio of sixteen operating with ordinary binary scaling action. Scaling with a ratio of ten is obtained in the present decade unit 42 through the use of a normally open gate E connected between the output of the flip-flop A and the input of the flip-flop B. A second, normally closed gate F is connected between the output of the flip-flop A and the input of the flip-flop D. The gate E is controlled by a potential supplied over a line 51 from the fourth flip-flop D, so that it is closed only whenever the latter flip-flop is in the "1" state. A suitable delay means d_1 is interposed in the line 51 to give adequate switching time. The normally closed gate F is controlled by a potential supplied over a line 52 which leads through

a delay device d_2 from an output terminal of the fourth flip-flop D, this gate thus being opened or closed whenever the fourth flip-flop is in the "1" or "0" state, respectively. It will be understood by those skilled in the art that the delay devices d_1 and d_2 connect to an output terminal of the flip-flop D which resides at, say, a high voltage when the flip-flop is in the "1" state, and at a low voltage when the flip-flop is in the "0" state. Assuming that the high voltage actuates the gates E and F, the latter will be respectively closed and opened shortly after flip-flop D is set to the "1" state, and will be respectively opened and closed shortly after the flip-flop D is restored to the "0" state. The output terminal 53 of flip-flop D, on the other hand, is associated in well-known manner with a differentiating and clipping circuit, so that sharp negative-going pulses appear thereon only when the flip-flop D switches from the "1" to the "0" state. These latter pulses form the input to the next decade unit 43.

Considering that the input terminal 54 of the flip-flop A forms the main input terminal for the decade unit 42, as input signals or pulses are supplied successively to that input terminal, the four tandemly connected flip-flops A, B, C, and D, behave as an ordinary binary scaling chain in response to the first eight pulses which are received. During this mode of operation, it will be seen that output pulses from the flip-flop A pass through an "or" circuit 55 and the normally open gate E to the input terminal of the flip-flop B. Similarly, output pulses from the flip-flop B pass directly to the input of the flip-flop C; and output pulses from the flip-flop C pass directly to the input terminal of the flip-flop D. Thus, assuming that all of the flip-flops were initially in their "0" states, eight pulses supplied to the input terminal 54 will result in the last flip-flop D being set to the "1" state, and the first three flip-flops A, B, and C being in their "0" states.

After the eighth pulse has been received and the flip-flop D has been switched to the "1" state, the control signals passed over the lines 51 and 52 will respectively close and open the gates E and F. The ninth input pulse, therefore, switches the first flip-flop to the "1" state and creates no output signal on the output terminal of that flip-flop device. The tenth input pulse returns the flip-flop A to the "0" state and creates an output pulse which cannot pass through the gate E, but which passes through an "or" circuit 56 and the open gate F directly to the input terminal of the fourth flip-flop D. This switches the fourth flip-flop D to the "0" state and creates a pulse on its output terminal 53 which forms the main output terminal for the scaling unit 42. As an incident to switching of the flip-flop D back to its "0" state, the control signals supplied over the lines 51 and 52 re-open the gate E and reclose the gate F, so that the unit 42 is returned to its original condition and is ready to repeat the scaling cycle described in response to the next ten input pulses received on the terminal 54. The counting or scaling action of the decade unit may thus be illustrated by the following table:

Input Pulses	Flip-Flop States			
	A(1)	B(2)	C(4)	D(8)
0	0	0	0	0
1	1	0	0	0
2	0	1	0	0
3	1	1	0	0
4	0	0	1	0
5	1	0	1	0
6	0	1	1	0
7	1	1	1	0
8	0	0	0	1*
9	1	0	0	1
10	0	0	0	0†

*Gates E and F close and open.

†Output pulse on terminal 53; gates E and F open and close.

This table shows the states of the four flip-flops A, B, C and D in the decade units 42 after each of ten input pulses has been received. When the tenth input pulse occurs,

one output pulse appears on the terminal 58 and the four flip-flops of the decade units are restored to their original states, i.e., are all set in the "0" state, so that the counting cycle of the unit will be repeated as the next ten input pulses are received.

It is possible to make a decade scaling unit, such as the scaling unit 42, scale by a factor of 5 if the input pulses are by-passed around the first flip-flop A. For this purpose, input pulses may be supplied to an alternate input line 59 instead of to the input terminal 54. The line 59 leads through the "or" gate 55 and the normally open gate E to the input of the second flip-flop B. With the three flip-flops B, C, D initially in the "0" state, the first four input pulses received over the line 59 pass through the normally open gate to the input of the flip-flop B. After the fourth pulse is received, however, the flip-flop D will be in the "1" state, causing the gates E and F to be respectively closed and opened. Thus, the fifth input pulse over the line 59 will pass through the "or" circuit 56 and the gate F directly to the input of the flip-flop D. This switches the flip-flop D from the "1" to the "0" state, producing an output pulse on the terminal 58 and restoring the flip-flops B, D and C to the "0" state. The manner in which the unit 42 scales by a factor of 5 if input pulses are by-passed around the first flip-flop A, is illustrated by the following table:

Input Pulse	Flip-Flop States			
	A	B	C	D
0	0	0	0	0
1	0	1	0	0
2	0	0	1	0
3	0	1	1	0
4*	0	0	0	1
5†	0	0	0	0‡

*Gates E and F respectively close and open.

†Gates E and F respectively open and close.

‡Output pulse on terminal 58.

The decade unit 42 may also be made to scale by a factor of 2 by bypassing input pulses around the first three flip-flops A, B, C and supplying them directly to an alternative input line 60 which leads to the input of the fourth flip-flop D. Under these circumstances, the last flip-flop D scales by a factor of 2 in the same manner as a single, isolated flip-flop, there being one output pulse appearing on the terminal 58 for every two input pulses passed over the line 60.

Considering now the scaling channel 40 as a whole (made up of the flip-flop 41, the six decade units 42-47, and the last flip-flop 48), one complete "counting cycle" as the term is here employed, is the operation of the chain in counting (from an original condition in which all the flip-flops are in their "0" state), the number of input pulses necessary to produce an output pulse on the final output terminal 50. It will be apparent that just before the last input pulse for any given counting cycle is received, all of the flip-flops which are effective in the scaling chain will be in the "1" state. The last input pulse restores all of the flip-flops to the "0" state, and this switching of the flip-flop to the "0" state produces a final output pulse on the terminal 50.

In order to make the scaling chain have different effective scaling ratios so that any one of a plurality of different predetermined numbers of signals must be received during different counting cycles, means are provided to change the effective "length" or over-all scaling ratio of the chain. This is done by providing a plurality of input terminals 61-69 for the scaling chain, any one of which may receive input signals or pulses, thus bypassing different numbers or combinations of the flip-flops at the front or left end of the scaling chain 40. Inspection of FIGS. 2A and 2B will show that if input pulses are supplied to the first input terminal 61, all of the flip-flops are effective in the scaling chain 40. Since the flip-flops 41 and 48 both

scale by factors of 2, and the six decade units 42-47 scale by factors of 10, the entire scaling ratio of the chain is $2 \times 10 \times 10 \times 10 \times 10 \times 10 \times 2$, or 4×10^6 . Thus, a total of 4 million pulses must be received from a signal source over the input terminal 61 before a final output pulse appears on the terminal 50.

If, however, input pulses are received over the terminals 62 or 63, the decade unit 42 will scale by factors of 10 or 5, respectively, and the first flip-flop 41 will be entirely bypassed or made ineffective. Under these circumstances, the effective scaling ratio of the scaling chain is 2×10^6 , or 1×10^6 , respectively.

With the foregoing examples in mind, the following table will be readily understood as showing the different total scaling factors created when the input pulses are supplied over different ones of the input terminals 61-69.

Line Receiving Input Pulses	Total Scaling Factor	Number of Input Pulses Required to Produce Transfer Pulse	Time Period With Input Frequency of 20,000 p.p.s., sec.
61	$2 \times 10 \times 10 \times 10 \times 10 \times 10 \times 10 \times 2$	4×10^6	200
62	$10 \times 10 \times 10 \times 10 \times 10 \times 10 \times 2$	2×10^6	100
63	$5 \times 10 \times 10 \times 10 \times 10 \times 10 \times 2$	1×10^6	50
64	$2 \times 10 \times 10 \times 10 \times 10 \times 10 \times 2$	4×10^5	20
65	$10 \times 10 \times 10 \times 10 \times 10 \times 2$	2×10^5	10
66	$5 \times 10 \times 10 \times 10 \times 10 \times 2$	1×10^5	5
67	$2 \times 10 \times 10 \times 10 \times 10 \times 2$	4×10^4	2
68	$10 \times 10 \times 10 \times 10 \times 2$	2×10^4	1
69	$5 \times 10 \times 10 \times 10 \times 2$	1×10^4	$\frac{1}{2}$

The foregoing table not only shows the total scaling factor of the scaling chain 40 and the number of input pulses required on the different input terminals 61-69 to produce a complete counting cycle and a final output pulse on the terminal 50, but it also shows in the last column on the right the time periods which will be measured off if those input pulses occur with a predetermined frequency, e.g., 20,000 pulses per second. It will be seen that by supplying input pulses at this frequency to any one of the nine input terminals of the scaling chain, time periods ranging from 200 seconds to as low as $\frac{1}{2}$ second may be measured off between the instant that the input pulses begin arriving at one of the input terminals 61-69 and the instant that an output pulse appears at the final terminal 50.

The input signals or pulses to be supplied to the scaling chain 40 are created in the first instance by a suitable recurring signal source 70 which may take any variety of forms such as a free-running multivibrator, a blocking oscillator or a sinusoidal oscillator combined with a pulse-shaping network. For purposes of the present explanation, it will be assumed that the source 70 produces input signals at a constant frequency of 20,000 pulses per second, although the source 70 need not necessarily produce signals at a constant repetition rate. Signals from the source 70 are passed through a gate 71 to a terminal 72. A counting cycle is commenced by a signal applied to a start terminal 5 which sets a flip-flop 73 to its "1" state. This produces a control signal on a line 73a which opens the gate 71 so that input signals begin appearing on the terminal 72. The terminal 72 may thus be considered as the output terminal of the pulse source 70 and on which appear recurring signals which are to be selectively routed to different ones of the scaling chain input terminals 61-69.

The problem exists of routing signals from the terminal 72 to any one of the input terminals 61-69 according to the selective information represented by the states of the cores 11-19. In accordance with the present invention, selective pulse routing apparatus 74 is interposed between the source 70, i.e., its terminals 72 and the plurality of terminals 61-69, this apparatus functioning to pass input signals to any one of the latter terminals according to the information which is received by the cores 11-19 and which designates the "count" or "time period" which is to be measured off. While the plurality of ter-

minals 61-69 may be considered as input terminals for the scaling chain 40, they may also be viewed as the output terminals for the selective routing apparatus 74.

In carrying out the invention in its preferred form, a plurality of bi-state devices 81-89 are employed, each corresponding to one of the terminals 61-69 and to one of the possible counts or time periods which may be selected. The bi-state devices 81-89 preferably take the form of magnetic cores similar in character to the cores 11-19 described above. These magnetic cores 81-89 10 all normally reside in the "0" state, but may be switched between their two states by magnetomotive forces of opposite senses applied thereto.

In order to set any one of the cores 81-89 to its "1" state when a corresponding one of the plurality of possible "counts" is to be measured off, interconnections 81a-89a are established between the cores 11-19 and corresponding ones of the cores 81-89. A transfer line 90 leads to all of the cores 11-19 and is connected with means for setting any of the cores 81-89 to its "1" state in response to an energization pulse or signal applied to the transfer line if the corresponding one of the cores 11-19 is then in its "1" state. The details of such transfer means will be made clear below with reference to FIG. 3; it need only be understood at this point that a pulse applied to the line 90 will drive any one of the cores 81-89 to its "1" state if a corresponding one of the cores 11-19 is in its "1" state.

After any one of the bi-state devices or cores 81-89 has been set to the "1" state to designate which of the possible counts or time periods is to be measured off, signals originating at the source 70 are transmitted by that particular bi-state device or core to the corresponding one of the terminals 61-69. For this purpose, means are provided to non-destructively interrogate all of the bi-state cores 81-89 in response to each signal from the source 70 and to pass a signal or pulse to any of the terminals 61-69 which corresponds to one of the cores 81-89 then in the "1" state. As here shown in FIGS. 2A and 2B, the output terminal 72 of the source 70 is connected directly to an "interrogate" line 76 which leads to all of the plurality of magnetic cores 81-89. The cores 81-89 are respectively paired with a second plurality of cores 91-99. The cores 91-99 are all normally in their "0" states. Each input signal passed over the interrogate line 76 tends to drive all of the cores 81-89 to their "0" states, in a manner which will be more fully explained below. Any of the cores 81-89 which is switched from its "1" to its "0" state in response to an input pulse applied to the interrogate line 76 causes the associated one of the cores 91-99 to be switched to the "1" state by an energization signal passed over the corresponding one of the transfer links 81b-89b.

To complete the selective routing apparatus 76, means are also employed which tend to drive all of the second plurality of cores 91-99 to their "0" states a predetermined time after the appearance of each input signal on the terminal 72. As here shown, the input terminal 72 is connected through a time delay device 77 to a "restore" line 78 which leads to all of the cores 91-99. The period of delay created by the device 77 is chosen to be less than the shortest time between successive ones of the input signals produced by the source 70. Thus, in response to each input pulse appearing on the terminal 72, a delayed signal is created on the restore line 78 and, in a manner to be explained in detail, drives all of the second cores 91-99 toward the "0" states. If any one of the cores 91-99 is at that instant in its "1" state, it will be switched back to its "0" state; those cores which are at that instant in their "0" state will simply be left in that condition.

Means are provided to produce two effects in response to the switching of any one of the second plurality of cores 91-99 from its "1" state to its "0" state. First, output lines 91a-99a lead from the respective cores 91-99

through buffer amplifiers 101-109 to the respective output terminals 61-69. These output lines 91a-99a are associated with output windings which transmit signals only in response to the switching of their associated cores from the "1" to the "0" state, as will be more fully detailed below. Secondly, restoring links 91b-99b are connected between each one of the cores 91-99 and the associated one of the cores 81-89 to serve as a means for switching any one of the cores 81-89 to its "1" state in response to switching of the corresponding cores 91-99 from its "1" to its "0" state. The detailed nature of these restoring links will be made clear subsequently with reference to FIG. 3.

In order that the interconnections and operation of the magnetic cores shown in FIGS. 2A and 2B may be better understood, exemplary ones of those cores and the windings thereon are shown in detail by FIG. 3. Consider first the cores 25, 18 and 15 shown in FIG. 3 and which, as indicated in FIG. 1, are a part of the shifting register 24. These shifting register cores are provided with input windings 25a, 18a, 15a; output windings 25b, 18b, 15b; and advance windings 25c, 18c, 15c. Assume that after one set of information has been partially shifted into the register 24, that the core 25 is in the "0" state and that cores 18 and 15 are in the "1" state. Advance pulses are then sequentially applied to the advance windings 15c, 18c and 25c in the order named, each such pulse tending to drive its core to the "1" state. There is no flux reversal in the cores 18 and 15 in response to these advance pulses, but the core 25 will be switched from the "0" state to the "1" state. As a result, a voltage is induced in the output winding 25b which causes current flow through a diode 115 to the input winding 18a, such current setting the core 18 to its "0" state. No output current flow occurs in the winding 18b because the induced voltage therein reversely biases the diode 116. Thus, the advancing action shifts the state of each core to the core immediately on the right. The input winding 25a may or may not be energized from the preceding core (not shown), depending upon whether the latter was in the "0" or "1" state when the shifting action begins.

When the advance windings are again sequentially pulsed, the core 18 will be reset from the "0" to the "1" state, and an output voltage will be induced in the winding 18b to create current flow through the diode 116. Such current energizes the input winding 15a and thus sets the core 15 to its "0" state.

Summarized, each set of advance pulses shifts the state of any core in the shifting register to the next succeeding core on the right. Thus, either of the cores 18 or 15 may be set to the "1" state in accordance with information received by the coding device 35 (FIG. 1) and shifted into the register 24.

Assume that after a complete block of information has been received by the shifting register that the core 18 is in the "1" state and the core 15 is in the "0" state, indicating a selected "count" of 2×10^4 or time period selection of one second. After the time cores have been set in accordance with the information received by the input terminals of FIG. 1, an energizing signal is applied (by means not shown) to the transfer line 90. This line leads to the junction 118 between windings 119a and 119b which are wound in opposite directions on the core 88. The winding 119a is returned to a common point 117 through a resistor 120, a diode 121, and a transfer winding 122 wound on the core 18. The sense of the winding 122 is such that the current flow therethrough from the diode 121 creates a magnetomotive force which tends to drive the core 18 to its "0" state. The winding 119b is returned to the common point 117 through a resistor 124 and a diode 125. The impedance of the transfer winding 122 to a current pulse passed therethrough will be one of two values, depending upon whether the core 18 is then resid-

ing in the "0" or the "1" state. The values of the resistors 120 and 124 are so proportioned that if the core 18 is in the "0" state, then current from the transfer line 90 will divide equally between the windings 119a and 119b, thus creating counteracting magnetomotive forces which leave the core 88 in its "0" state. On the other hand, if the core 18 is in its "1" state, the impedance of the winding 122 has a different value so that current flowing from the transfer line 90 divides unequally between the windings 119a, 119b, creating a net magnetomotive force in the core 88 which drives the latter to its "1" state. An incident to this current flow through the transfer winding 122, the core 18 is returned from its "1" state to its "0" state. It will be apparent, therefore, that a current pulse appearing on the transfer line 90 acting in the split transfer circuit or link 88a will drive the core 118 toward its "0" state, and will switch the core 88 to its "1" state if the core 18 at that time is in its "1" state. On the other hand, if the core 18 is in its "0" state when a transfer pulse occurs on the line 90, the cores 88 and 18 will be left in their "0" states.

The transfer link 85a between the cores 15 and 85 is identical to the link 88a just described in detail. The common point 117 in the link 88a leads in series to the junction 127 in the link 85a, thus indicating that current pulses applied to the transfer line 90 pass in series through all of the transfer links 81a-89a. Thus, in response to a transfer pulse appearing on the line 90, the link 85a will serve to set the core 85 to its "1" state if the core 15 at that time is in its "1" state, returning the latter core to its "0" state. Conversely, if the core 15 is in its "0" state, the core 85 will be left in its "0" state. The transfer links 81a-89a shown in FIG. 2 are all organized and operate in the same manner as the links 88 and 85a which are shown in detail by FIG. 3.

The transfer link 88b which interconnects the core 88 and its paired core 98 is substantially like the split transfer loop previously described for the transfer link 88a. That is, the interrogate line 76 leads to a junction 128 between two oppositely wound windings 129a and 129b on the core 98. The winding 129a is returned through a resistor 130, a diode 131 and a transfer winding 132 to a common point 133; while the winding 129b is returned directly to the same point through a resistor 134 and a diode 135. In response to a current pulse of the polarity indicated on the interrogate line 76, therefore, the core 88 will be driven towards its "0" state, while the core 98 will be left in its "0" state or switched to its "0" state if the core 88 at that instant is in its "0" or "1" states, respectively. The transfer link 85b between the cores 85 and 95 is identical to and connected in series with the transfer link 88b just described. Thus, it will be apparent that in response to each interrogate pulse appearing on the line 76 the transfer connections 81b-89b in FIG. 2 will serve to switch any one of the cores 91-99 to the "1" state if the corresponding one of the cores 81-89 is in its "1" state. Any of the cores 81-89 which is in its "1" state when the interrogate pulse occurs will be returned to its "0" state.

The restore line 78 as shown in FIG. 3 passes in series through restore windings 136 and 137 on the cores 98 and 95. The sense of these restore windings is such that current flow through them creates a magnetomotive force in the cores 98 and 95 which tends to drive flux in those cores to the "0" state. If either of the cores 98 or 95 was in the "0" state before the "restore" signal appeared, then no output response is created in output windings 138 or 139 disposed on those cores. If, however, the core 98 has been set to its "1" state before a restore pulse appears on the line 78, then that restore pulse will switch the core 98 to its "0" state and induce a voltage in the output winding 138 which creates current flow through an associated diode 140, such current passing over the output link 98a to the associated buffer amplifier shown in FIG. 2. Thus,

it will be clear that a "restore" signal on the line 78 in FIG. 2 drives all of the cores 91-99 toward their zero states, and any one of such cores which in response switches from the "1" to the "0" state will produce an output signal on the corresponding one of the output lines 91a-99a.

As previously indicated in connection with FIG. 2, restore links 91b-99b are provided between the cores 91-99 and the associated cores 81-89 to reset any one of the latter to its "1" state whenever the associated core of the group 91-99 is switched from its "0" to its "1" state. As shown in detail by FIG. 3, the restore link 98b comprises a restore output winding 141 wound on the core 98 and connected in series through a diode 142 to a restore input winding 144 on the core 88. The sense of the winding 141 is such that when flux within the core 98 switches from the "1" to the "0" state, the voltage induced in the winding 141 is of a polarity to create current flow through the diode 142. This current flow through the winding 144 creates a magnetomotive force in the core 88 which drives the latter to its "1" state. Thus, if the core 98 is switched from its "1" to its "0" state, not only is an output signal produced on the output line 98a, but the core 88 is restored to its original "1" state.

The restore link 95b connected between the core 95 and the core 85 is identical and functions in the same manner as the restoring link 98b just described.

At the completion of a counting cycle, that one of the cores 81-89 previously set to the "1" state is "cleared" or returned to the "0" state so that a new "count" may be selected. This is done by applying a "clear" current pulse to a clear line 147 (FIGS. 2 and 3). The clear line leads in series through windings (exemplified by winding 143 and 149 in FIG. 3) on all the cores 81-89, such windings being wound in a sense to drive the cores toward their "0" states. Any one of the cores which is switched to its "0" state when cleared produces no effect on the associated cores, since the diodes in the transfer links 81a-89a and 81b-89b prevent responsive current in those links.

Assuming now that at the beginning of a cycle of operation the core 18 was in its "1" state and the core 15 in its "0" state, a transfer pulse appearing on the line 90 sets the core 88 to its "1" state and leaves the core 85 in its "0" state. With the commencement of pulses from the source 70 appearing on the terminal 72 (FIG. 2), recurring interrogating pulses are applied to the line 76. The device 77 produces a pulse appearing on the restore line 78 shortly after each such interrogate pulse. The core 88 will be driven to its "0" state and the core 98 driven to its "1" state in response to the first input or interrogating pulse. Then the core 98 will be driven to its "0" state in response to the first restore pulse to produce an output signal on the output line 98a and to produce a signal in the restore link 98b which resets the core 88 to its original "1" state. So long as input pulses from the source 70 continue to occur, therefore, the cores 88 and 98 will be switched from one state to the other and back to their original states in response to each such input pulse. Each time this switching of the core 98 back to its "0" state occurs, an output pulse will appear on the output link 98a. That is, there will be one output pulse on the line 98a for each input pulse appearing on the terminal 72. On the other hand, because the core 15 was assumed to originally be in the "0" state and the transfer pulse appearing on the line 90 thus left the core 85 in its "0" state, the alternate interrogate pulses on the line 76 and the restoring pulses on the line 78 simply leave the cores 85 and 95 in their "0" states. No switching of the core 95 occurs, and no output pulses at all appear on the output line 95a.

It is to be understood that all of the transfer links 81a-89a shown diagrammatically in FIG. 2 are identical in organization and operation with the links 88a and 85a which are shown in detail by FIG. 3. Similarly, all of the transfer links 81b-89b shown in FIG. 2 are identical to the links 88b and 85b shown in detail by FIG. 3.

Moreover, the restore links 98b and 95b shown in detail by FIG. 3 indicate the organization and operation of all of the restore links 91b-98b illustrated diagrammatically in FIG. 2. The restore line 78 shown in FIG. 2 as leading to all of the cores 91-99 passes in series through restore windings on all of these later cores, as is illustrated by the restore winding 136, 137 in FIG. 3. Finally, the output links 91a-99a are all identical in their organization and operation to the output links shown in detail by FIG. 3 and constituted by the output windings 138 and 139 on the cores 98 and 95, such output windings being connected in series with diodes which transmit an output signal only when the associated core switches from its "1" to its "0" state.

Résumé of operation

With the foregoing in mind, the operation of the selective counting apparatus as a whole may now be described. At the beginning of a cycle of operation, the flip-flop 73 will be in its "0" state and the gate 71 closed, so that no input pulses appear on the terminal 72. A set of information which by the first three characters therein designates the desired "count," is received on the input terminals 36 (FIG. 1) and will be shifted into the register 21-24. A particular one of the cores 11-19 will be set to its "1" state to designate which of the several time periods or numbers of pulses is to be measured off. Following this shifting of information into the registers, a transfer pulse will be applied to the transfer line 90 and a particular one of the cores 81-89 which corresponds to that one of the cores 11-19 previously set to its "1" state will be switched to the "1" state, thereby designating which of the several "counts" is to be measured off. Assume that the core 15 in FIG. 2 was initially set to the "1" state, while the remaining cores 11-14 and 16-19 were left in their "0" states. The appearance of a transfer pulse on the line 90 will thus set the core 85 to its "1" state and leave the cores 81-84 and 86-89 in their "0" states.

The gate 71 is now opened in response to a start signal applied to the terminal S, so that recurring input signals are passed from the source 70 through the gate to the terminal 72. These recurring input signals appear sequentially on the interrogate line 76, each one tending to drive all of the cores 81-89 to its "0" state and thus switching any one of those cores which was in its "1" state to the "0" state. Pursuing the example initiated above, if the core 85 was in the "1" state, that core will be returned to the "0" state in response to each interrogate pulse appearing on the line 76. As a result of this switching of the core 85, the interrogate link 85b will cause the associated core 95 to be switched to its "1" state. Thus, each input pulse appearing on the terminal 72 sets any of the cores 91-99 to its "1" state if the associated one of the cores 81-89 was in its "1" state.

After a predetermined time delay produced by the device 77 from the instant that each input pulse appears on the terminal 72, a restore pulse appears on the line 73. This restore pulse on the line 78 tends to drive all of the cores 91-99 to their "0" states, and thus will switch any one of those cores originally in its "1" state. If the core 95 has been set to its "1" state in response to the previous interrogating pulse, the restore pulse will switch it back to the "0" state. As an incident to switching of any core 91-99, from its "1" to its "0" state, an output signal is passed through the associated buffer amplifier to the associated one of the output terminals 61-69. Moreover, in response to the switching of any of the cores 91-99 from its "1" to its "0" state, the associated restore link 91b-99b causes the associated one of the first set of cores 81-89 to be restored to its "1" state. Thus, the "1" state of any of the cores 81-89 is non-destructively sensed by each input pulse appearing on the terminal 72 and an output pulse is generated on the output terminal which corresponds to that core which is in the "1" state.

Pursuing the example, initiated above, the alternate

interrogate pulses on the line 76 and restore pulses on the line 78 will cause switching of the core 95 first to its "1" state and then to its "0" state. Each time that the core 95 returns to its "0" state, a pulse will appear on the terminal 65 which leads to the input terminal of the flip-flop A in the decade scaling unit 43. Thus, the effective scaling ratio of the scaling chain 40 will be 2×10^5 , and a total of 200,000 input pulses must appear on the terminal 72 and be transmitted to the terminal 65 before a final output pulse appears on the scaling chain terminal 50. Thus, the setting of the core 15 to its "1" state and the subsequent operation of the apparatus will result in the scaling chain 40 measuring off 200,000 pulses before signifying by an output pulse on the terminal 50 that such number of pulses has been received. If the pulse source 70 has a constant frequency, for example, 20,000 pulses per second, then an elapsed time of 10 seconds will occur between the opening of the gate 71 and the appearance of an output pulse on the terminal 50.

In like manner, if any of the cores 11-19 is originally set to the "1" state by information received on the terminals 36 (FIG. 1), then the numbers of pulses which will be generated by the source 72 during one complete counting cycle, and the time periods occupied by such counting cycle, will have the values which are set forth in the preceding table.

In order to terminate the operation of the scaling chain after it has completed any counting cycle, the final output pulse appearing on the terminal 50 is passed over a line 160 to an input terminal of the flip-flop 161. This output pulse resets flip-flop 161 to its "0" state, the control potential passed over the line 73a closes the gate 71, thereby terminating the appearance of input pulses on the terminal 72. The final output pulse on the terminal 50 is also passed over a line 164 to the "clear" terminal associated with the cores 81-89. In response to this pulse, therefore, all of the cores 81-89 are driven toward their "0" states, and that one of these cores which was previously in its "1" state will be returned to its "0" state without affecting any of the associated cores 91-99.

The next set of information, which may have been shifted into the shifting registers of FIG. 1 during the counting cycle described, may now be transferred to the cores 81-89 by a transfer signal applied to the transfer line 90. Following this, a start signal may be applied to the terminal S to set the flip-flop 73 to its "1" state. With this, the control signal passed over the line 73a opens the gate 71 so that pulses generated by the source 70 appear on the terminal 72 and the counting or scaling action previously described is started for the next cycle. In each instance, the particular one of the cores 81-89 which was set to its "1" state before the beginning of a scaling cycle determines which of the terminals 61-69 will receive input pulses, and thus the total number of pulses which will be measured off during that cycle.

It will be apparent from the foregoing that the present arrangement makes it possible to measure off any one of different numbers of pulses generated by the source 70, and to measure off any one of a plurality of time periods if the pulse source 70 operates at a substantially constant frequency. Since the bi-state elements or cores employed therein are switched repetitively in response to input pulses and serve to transmit output pulses to a selected one of the scaling chain input terminals 61-69, the principal components of the selective routing apparatus 74 do not involve the use of vacuum tubes or transistors. The use of vacuum tubes or transistors, except as power amplifiers, is substantially eliminated. The arrangement is characterized by relatively simple structural components and a high degree of reliability in operation.

We claim as our invention:

1. In apparatus for measuring off different selected numbers of recurring input signals received from a source, the combination comprising a scaling chain having a plurality of scaling units connected in tandem relation with

the last such unit having an output terminal, a plurality of input terminals leading to different points in said scaling chain to provide different over-all scaling ratios for the chain, a plurality of bi-state devices adapted to reside in either "1" or "0" states and normally residing in the "0" state, each of said bi-state devices corresponding to one of said input terminals, means for setting one of said devices to its "1" state according to the particular selected number of signals which is to be measured off, means responsive to each of said input signals for driving all of said bi-state devices toward their "0" states, means responsive to the switching of each of said bi-state devices from its "1" to its "0" state for restoring that device to its "1" state after a time delay which is less than the period between said recurring input signals, means responsive to the switching of any of said bi-state devices from its "1" to its "0" state for creating a signal on the corresponding one of said input terminals, and means responsive to a signal on the output terminal of said scaling chain for clearing all of said bi-state devices to their "0" states without transmitting a signal to any of said input terminals.

2. In apparatus for measuring off different selected numbers of recurring input signals received from a source, the combination comprising a scaling chain having a plurality of scaling units connected in tandem relation with the last such unit having an output terminal, a plurality of input terminals leading to different points in the scaling chain to provide different over-all scaling ratios for the chain, a plurality of pairs of first and second magnetic cores, each said pair of cores corresponding to one of said plurality of input terminals, each of said magnetic cores having a substantially rectangular hysteresis characteristic and being susceptible of residing in "0" or "1" states represented by the direction of residual magnetic flux therein, means for selectively setting to its "1" state the first core of the pair of cores which corresponds to the particular selected number of input signals which is to be measured off, means responsive to each of said input signals for driving the first core in all of said pairs toward its "0" state, means responsive to switching of the first core in any of said pairs from the "1" to the "0" state for switching the second core in that pair to the "1" state, means responsive to each of said input signals for driving the second cores in all of said pairs toward the "0" state after a time delay which is shorter than the period between said recurring input signals, means responsive to the switching of the second core in any of said pairs from the "1" to the "0" state for transmitting a signal to the corresponding one of said plurality of terminals, means responsive to the switching of any of said second cores from its "1" to its "0" state for switching the corresponding core from its "0" to its "1" state, and means responsive to the appearance of an output signal on said output terminal for driving all of said first cores toward their zero states without affecting any of said second cores.

3. In apparatus for measuring off different predetermined numbers of recurring signals, the combination comprising a source of recurring signals, a scaling chain having a plurality of input terminals each of which leads to a different point along the chain and which causes the latter to have a different effective scaling ratio when input signals are applied to that terminal, a plurality of pairs of magnetic cores each having a substantially rectangular hysteresis characteristic and susceptible of residing in either a "0" or a "1" state, each of said pairs of cores corresponding to one of said different predetermined numbers, means for setting the first core of a pair which corresponds to a selected one of said predetermined numbers to its "1" state, means for driving the first cores of all of said pairs toward their "0" states in response to each signal from said source, means responsive to switching of the first core in each of said pairs from its "1" to its "0" state for setting the second core of that

pair to its "1" state, means for driving the second core in all of said pairs towards its "0" state a predetermined time instant after operation of said first-mentioned driving means, means responsive to switching of the second core in any one of said pairs from the "1" to the "0" state for transmitting an input signal to the corresponding one of said input terminals, and means for clearing and restoring to its "0" state the first core in all of said pairs in response to the completing of one counting cycle by said scaling chain.

4. The combination set forth in claim 3, further characterized in that said source of recurring signals is a substantially constant frequency source, so that the selective counting of said different numbers of signals also selectively measures off different time periods.

5. In apparatus for selectively measuring off different numbers of recurring signals, the combination comprising a scaling chain having a plurality of scaling units connected in tandem relation and an output terminal at the last such scaling unit, a plurality of input lines leading to different points along said scaling chain and respectively by-passing different numbers of said scaling units to create different over-all scaling ratios for said chain, a first plurality of magnetic cores each corresponding to one of said input lines, a second plurality of magnetic cores each corresponding to one of said input lines, said cores having a substantially rectangular hysteresis characteristic and being susceptible of residing in "0" or "1" states depending upon the sense of the residual magnetism therein, said cores normally residing in the "0" state, means for setting any one of said first cores to its "0" state to designate the selection of the corresponding one of said different numbers of said recurring signals to be measured off, a source of recurring signals which are spaced apart in time, a single interrogate line associated with all of said first cores, means for applying each signal from said source to said interrogate line, means responsive to a signal on said interrogate line for driving any of said first cores which is in its "1" state to its "0" state, means responsive to switching of any of said first cores from the "1" to the "0" state for switching the corresponding one of said second cores to its "1" state, a restore line, a time delay device interconnected between said source and said restore line, means responsive to a signal on said restore line for switching any of said second cores which is in the "1" state to the "0" state, an output winding on each of said second cores, means interconnecting each said output winding with a corresponding one of said input lines to produce a signal on any input line when the corresponding core switches from its "1" to its "0" state, and means responsive to switching of any of said second cores from the "1" to the "0" state for restoring the associated first core to its "1" state.

6. In apparatus for selectively routing recurring input signals appearing on a first terminal to any one of a plurality of output terminals, the combination comprising a plurality of bi-state devices adapted to reside in either "1" or "0" states and normally residing in the "0" state, each of said bi-state devices corresponding to one of said plurality of terminals, means for setting one of said devices to its "1" state according to a selected one of said plurality of terminals which is to receive said input signals, means responsive to each of said input signals for driving all of said bi-state devices to their "0" states, means responsive to the switching of each of said bi-state devices from its "1" to its "0" state for restoring that device to its "1" state after a time delay which is less than the period between said recurring input signals, and means responsive to the switching of any of said bi-state devices from its "1" to its "0" state for creating a signal on the corresponding one of said output terminals.

7. In apparatus for selectively routing recurring input signals appearing on a first terminal to any one of a plurality of output terminals, the combination comprising a plurality of bi-state devices each corresponding to one

of said output terminals and adapted to reside in either a "0" or "1" state, said bi-state devices normally residing in the "0" state, means for setting one of said bi-state devices in its "1" state according to a selected one of said output terminals which is to receive said signals, an interrogate line connected to said first terminal to receive said input signals, means including connections from said interrogate line to all of said bi-state devices for switching any one of such devices which is in the "1" state to the "0" state in response to each said input signal, a restore line, a time delay device interconnected between said input terminal and said restore line, means including connections from said restore line to all of said bi-state devices for switching any one of such devices which is in the "0" state to the "1" state in response to each delayed input signal, means responsive to switching of any of said bi-state devices from a first of said states to the second of said states for producing an output signal on the corresponding one of said output terminals, and means for clearing said bi-state devices prior to the next operation of said setting means.

8. In apparatus for selectively routing recurring input signals appearing on a first terminal to any one of a plurality of output terminals, the combination comprising a plurality of magnetic cores each corresponding to one of said output terminals, each of said cores having a substantially rectangular hysteresis characteristic and being susceptible of residing in "0" or "1" states represented by the direction of residual magnetism therein, said cores normally residing in the "0" state, means for setting a selected one of said cores to the "1" state to designate which of said output terminals is to receive signals, means for driving all of said magnetic cores to their "0" states in response to each input pulse appearing on said first terminal, means responsive to switching of flux in said selected core from the "1" state to the "0" state for restoring the said selected core to its "1" state, and means interconnecting each said core with the corresponding output terminal for creating a signal on the latter only in response to switching of that core from the "1" to the "0" state. 40

9. In apparatus for selectively routing recurring input signals appearing on a first terminal to any one of a plurality of output terminals, the combination comprising a plurality of pairs of first and second magnetic cores, each 5 pair of cores corresponding to one of said plurality of terminals, each of said magnetic cores having a substantially rectangular hysteresis characteristic and being susceptible of residing in "0" or "1" states represented by the direction of residual magnetic flux therein, means for selectively setting to its "1" state the first core of the pair of cores which corresponds to any selected one of said plurality of terminals which is to receive signals, means responsive to each of said input signals for driving the first core in all of said pairs toward its "0" state, means 10 responsive to switching of the first core in any of said pairs from the "1" to the "0" state for switching the second core in that pair to the "1" state, means responsive to each of said input signals for driving the second core in all of said pairs toward the "0" state after a time delay 15 which is shorter than the period between said recurring input signals, means responsive to the switching of the second core in any of said pairs for transmitting a signal to the corresponding one of said plurality of output terminals, and means responsive to the switching of any of said second cores from its "1" to its "0" state for switching the corresponding first core from its "0" to its "1" state. 20
